2

Seeds from the controlled cross were obtained. The seeds were sown and plants were grown for evaluation. A single plant was selected in June 2017 and subsequently named 'KLEPZ22698'. In July 2017 'KLEPZ22698' was first vegetatively propagated by vegetative stem cuttings in Stuttgart, Germany. 'KLEPZ22698' was found to reproduce true to type in successive generations of asexual propagation via stem cuttings in Stuttgart, Germany.

SUMMARY

The following are the most outstanding and distinguishing characteristics of this new variety when grown under normal horticultural practices in Latina, Italy.

- 15 1. Red flower color with a light pink border and center;
2. A lack of zonation; and
3. A large flower size.
